(57) **CLAIM**

The ornamental design for an adult portable sound machine, as shown and described.

DESCRIPTION

FIG. 1 is a perspective view of an adult portable sound machine showing my first design, as viewed from the top and front.

FIG. 2 is a front profile view of the adult portable sound machine showing my first design.

FIG. 3 is a back profile view of the adult portable sound machine showing my first design.

FIG. 4 is a first side profile view of the adult portable sound machine showing my first design.

FIG. 5 is a second side profile view of the adult portable sound machine showing my first design.

FIG. 6 is a top plan view of the adult portable sound machine showing my first design.

FIG. 7 is a bottom plan view of the adult portable sound machine showing my first design.

FIG. 8 is a perspective view of an adult portable sound machine showing my second design, as viewed from the top and front.

FIG. 9 is a front profile view of the adult portable sound machine showing my second design.

FIG. 10 is a back profile view of the adult portable sound machine showing my second design.

FIG. 11 is a first side profile view of the adult portable sound machine showing my second design.

FIG. 12 is a second side profile view of the adult portable sound machine showing my second design.

FIG. 13 is the top plan view of the adult portable sound machine showing my second design; and,

FIG. 14 is the bottom plan view of the adult portable sound machine showing my second design.

The details shown in broken lines illustrate features that form no part of the claimed designs.

1 Claim, 6 Drawing Sheets
